GAS LEAK DETECTOR

Eugene F. Griss, 2851 Albon St.,
Maumee, Ohio 43537

Filed Oct. 24, 1972, Ser. No. 300,142

Term of patent 14 years

Int. Cl. D23—01

U.S. Cl. D23—1

FIG. 1 is an end elevational view of a gas leak detector embodying my new design;

FIG. 2 is a bottom elevational view;

FIG. 3 is a side elevational view;

FIG. 4 is a top plan view;

FIG. 5 is a side elevational view from the opposite side shown in FIG. 3; and

FIG. 6 is an end elevational view of the opposite end of the leak detector shown in FIG. 1.

I claim:

The ornamental design for a gas leak detector, substantially as shown.
